Primary Examiner—Mimosa De(74) *Attorney, Agent, or Firm*—Heslin Rothenberg Farley & Mesiti P.C.(57) **CLAIM**

The ornamental design for a seat frame, as shown and described.

DESCRIPTION

FIG. 1 is a perspective view of a seat frame in accordance with the new design;

FIG. 2 is a front elevational view thereof;

FIG. 3 is a left side elevational view thereof, a right side elevational view being a mirror image thereof;

FIG. 4 is a rear elevational view thereof; and,

FIG. 5 is a top view thereof.

The broken lines in the figures are for illustrative purposes only and form no part of the claimed invention.
